UNITED STATES PATENT OFFICE.

WILLIAM L. GUMPERZT, OF HARTFORD, CONNECTICUT, ASSIGNED BY HISNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,285,134.

Specification of Letters Patent. Patented Nov. 19, 1918.

Application filed July 11, 1918. Serial No. 778,451.

To all whom it may concern:

Be it known that I, WILLIAM L. GUMPERZT, a subject of the King of Great Britain, residing in Hartford, in the county of 5 Hartford and State of Connecticut, have invented certain new and useful Improvements in Combined Type-Writing and Computing Machines, of which the following is a specification.

10 This invention relates to a combined type-writing and computing machine of the Underwood-Hanson type and more particularly to a new and improved mechanism for enabling subtracting computations, and is 15 an improvement on an application of Hans Hanson, No. 626,550, filed May 11, 1911, and an application of John N. Thornton, No. 769,132, filed May 22, 1913. I am also aware of an invention made by Hans Hanson, embodied in an application, Serial Number 20 790,453, filed September 18, 1913, as to the common or conflicting subject-matter of which application and my present application I make no claim.

25 In this type of machine the several digits of a number are first accumulated or set up and then run up concomitantly in the computing wheels. The setting up is effected by projecting individuals of a nest of pins beyond their fellows by a method of cross selection, so as to correspond with the particular numeral keys actuated and to the exact denominational columns in which the numbers corresponding to the keys are written.

30 35 The running up of the numbers in the computing wheels is accomplished by a general operator, which engages the set pins to move the members bearing the same amounts corresponding to the set pins, which movements are transferred to the corresponding computing wheels.

In the machine used to illustrate this invention, the computing wheels are always rotated in the same direction for both addition and subtraction. The complementary method is used in subtraction, so that the computing wheels will be rotated each a complete revolution less the value of the numeral key struck in the column accordan- 40 therewith. In other words, the computing wheels having numbers subtracted therefrom are rotated forward amounts corresponding to the complements of the accordantly struck

numeral keys using one less than the exchange value (that is, nine in the decimal system) as a base or measure in obtaining the complement. 55

To do this, the pin-setting mechanism is readjusted so that when the numeral keys are actuated it will set up pins corresponding with the complements thereof instead of the exact values. 60

Of course if the zero key should happen to be struck in any column, it is essential that the complement thereof or the "9" pin should be set up on the pin-bearing member in the particular denominational column, so that the associated computing wheel will be rotated nine-tenths of a revolution. This condition is anticipated in setting the machine for subtraction by setting up all of the "9" pins concomitantly before any digit of a particular number to be subtracted is accumulated, and then when any digit is accumulated in any particular column, that is other than zero, and the corresponding pin set, this "9" pin may be again unset. Means is further provided for giving the computing wheel of lowest denomination (that is, the units or cents wheel) the additional step of movement which is necessary in complementary subtracting. 70 75

The actuation of the general operator may be controlled automatically from the carriage during the traveling movements thereof or by an arrangement of a tripping mechanism which controls the connection of an automatic clutch between the motor and the general operator. 80 85

Subtraction-setting may also be controlled automatically from the carriage. In the application No. 769,132, above mentioned, in order to set the machine for subtraction, the subtracting operation is anticipated in the column previous to that in which the subtraction is to be carried out. In the present case the machine is set for subtraction as the carriage enters the computing zone or column in which the subtracting operation is to be carried out. This is effected by a tappet carried by the carriage and actuating a tripping linkage to bring into play a motor which actuates the several parts of the subtraction-setting mechanism to set up a subtracting condition. 90 95 100 105

In order that this subtraction-setting mechanism may not race under the impulse of its motive means, a damper or retarder is provided for cushioning the action and preventing the disruption of the parts actuated in a subtraction-setting operation.

Provision is further made to prevent the setting action of the subtraction-setting mechanism during a movement of the general operator. Further, means is provided for preventing a subtraction setting while the tabulating mechanism is in play, and a further means is provided for preventing the tripping of the subtraction-setting mechanism when the computing mechanism is thrown out of operation. As to these features relating to the subtraction-setting, as far as they are found in the application No. 790,453, above mentioned, I make no claim, but do claim the specific structure not found in such application or the prior art.

In case the subtraction-setting mechanism should be only partially actuated so that the mechanism would be neither set for addition nor subtraction, means is provided for preventing the complete actuation of the numeral keys, and further for preventing the actuation of the computing mechanism, so that the operative would be aware of the disarrangement of the parts of the computing mechanism.

Other features and advantages will hereinafter appear.

In the accompanying drawings—

Figure 1 is a sectional view taken from front to rear with parts omitted for the sake of simplicity.

Fig. 2 is an enlarged detail view of the toggle action for setting the mechanism for subtraction with the lock for holding the subtraction rod in its actuated position. This lock is shown in its effective position with the subtraction rod in its rearmost position.

Fig. 3 is a detail of the manual means for throwing out the computing mechanism shown in its effective position corresponding to the disconnection of the computing mechanism.

Fig. 4 is a skeleton perspective view showing the relative arrangement of the controlling mechanism carried by the carriage to the subtraction-setting mechanism and motor-connecting mechanism.

Fig. 5 is an enlarged vertical section of the latches for the motor control and the subtraction-setting control.

Fig. 6 is a detail section showing one of the tappets in position on the bars carried by the carriage.

Fig. 7 is a rear view in elevation of the machine as a whole with parts broken away to show the underlying structure.

Fig. 8 is a skeleton perspective view showing the relation of the controlling cam which

governs the effectiveness of the carriage-carried tappet.

Fig. 9 is a detail view showing the motor trip in rear elevation.

Fig. 10 is a fragmentary top plan view 76 showing the parts illustrated in Fig. 9.

Fig. 11 is a detail view of a tabulating stop carried by the carriage, which is ineffective to control the connection of the motor to drive the general operator. 75

Fig. 12 is a detail view of a carriage-carried tappet or stop which is effective to control the connection of the motor to drive the general operator. 75

Fig. 13 is an enlarged detached top plan 80 view of the pin-setting linkages showing the same connected for an adding operation and with parts broken away to show the particular fin-bearing structure of the arms on some of the rock shafts. 85

Fig. 14 is a view of the parts shown in Fig. 13 taken in vertical elevation with parts broken away to show the underlying structure.

Fig. 15 is a detail view of one of the fin-bearing arms showing it in its subtracting position and showing the relative arrangement of the fin thereon to the locking fin as distinguished from the showing in Fig. 13. 90

Fig. 16 is a detail perspective view of one 95 of the fin-bearing arms.

Fig. 17 is a collected view of the computing mechanism showing its relation to the computing wheels.

Fig. 18 is a detail view of the pin-bearing 100 rack bars with the means for setting the "9" pins.

Fig. 19 is an enlarged fragmentary view in vertical section showing the mechanism in the act of setting the "9" pins and also 105 showing the subtraction rod as partially drawn rearwardly by the automatic subtraction-setting mechanism and in fact almost in its rearmost position.

Fig. 20 is a detail view of one of the pin-bearing rack bars showing the "9" pin restoring bar in its normal ineffective position. 110

Fig. 21 is a view similar to Fig. 20, with the exception that the "6" pin has been set 115 up at the same time that the "9" pin has been unset.

Fig. 22 is a top plan view of the rack bar of lowest denomination, that is, the units or cents rack bar, showing its relation to a 120 supernumerary bar with a cut-out portion or projection carried thereby, whereby the bar of lowest denomination may be given an additional step of movement in a subtracting operation.

Fig. 23 is a vertical section taken at right angles to the view shown in Fig. 22 and showing the trigger on the supernumerary bar set to give an additional step movement to the units or cents bar. 125

Fig. 24 is a detail view of the automatic subtraction-setting mechanism showing the same in its normal position.

Fig. 25 is a view similar to Fig. 24, with the exception that the latch has been released and the shaft started on its rotation to effect a subtraction setting.

Fig. 26 is a vertical section showing the parts illustrated in Fig. 24 and taken at right angles thereto.

Fig. 27 is a view in elevation showing the parts illustrated in Fig. 26 and taken at right angles thereto.

Fig. 28 is a view similar to Figs. 24 and 25, showing a further movement of the subtraction-setting shaft, in which the latch-releaser is being cammed back to its normal raised position.

Fig. 29 is a view similar to Figs. 24, 25 and 28, with the exception that the subtraction-setting shaft has moved around substantially to the position at the end of its subtraction-setting rotation wherein the latch-releaser has been returned to its normal raised position, also illustrating the sencer in its effective position.

Fig. 30 is a continuing view similar to Fig. 29, illustrating the shaft returning to restore the power in the spring motor therefore during a subsequent forward movement of the general operator.

Fig. 31 is a detail view of the stopping or locking cam which determines the end of the initial rotation of the subtraction-setting shaft.

Fig. 32 is a detail view of the auxiliary motor for actuating the subtraction-setting mechanism.

Fig. 33 is a detail view of the gear, showing the clutch socket thereof, which gear is used as part of the train in rewinding the auxiliary motor or spring for the subtraction-setting mechanism.

Fig. 34 is a detail view of the pneumatic retarder or governor for controlling the speed of action of the subtraction-setting mechanism under the impulse of its auxiliary spring motor, the parts being shown in their initial position before the starting into motion of the subtraction-setting mechanism.

Fig. 35 is a view similar to Fig. 34, with the exception that the piston plunger has been forced in by the rotation of the subtraction-setting shaft owing to the unwinding of the spring motor.

Fig. 36 is a detail view in vertical section of the automatic cam for actuating the subtraction-setting mechanism by drawing the subtraction rod rearwardly.

Fig. 37 is a contracted plan view of the parts shown in Fig. 36.

Fig. 38 is a detail section through the driving train between the motor and the general

operator, showing the relative arrangement of the parts of the clutch when in their silent or disconnected positions.

Fig. 39 is a detail view of the cross head and crank arrangement whereby the rotating motion of the motor is translated into a reciprocating motion of the general operator.

Fig. 40 is a detail section taken at right angles to the section shown in Fig. 38 and disclosing the specific details of the clutch which forms the controlling element in the train of gearing between the general operator and the motor. The clutch is shown in its disconnected or ineffective position with the train of gearing interrupted.

Fig. 41 is a view somewhat similar to Fig. 40 with the exception that the stop pin has been removed so as to permit the closing of the clutch and thus complete the train of gearing between the motor and the general operator.

Fig. 42 is an enlarged contracted skeleton perspective view showing details of the controlling mechanism whereby the subtraction setting may be actuated from the carriage, with the various locks and throw-out devices for preventing the bringing into play of the subtraction-setting mechanism at inopportune times.

Fig. 43 is a detail section through the camming pawl carried by the carriage, which trips the subtraction-setting mechanism.

Fig. 44 is a detail perspective view showing the safety connection between the subtraction rod and the pin-setting mechanism shifter bar, which will enable a forced relative movement between the parts in case of jamming or fouling.

Fig. 45 is a detail perspective view of the tripping or camming pawl carried by the tappet, which controls the tripping of the subtraction-setting mechanism.

Referring more particularly to the separate parts of this invention, as embodied in the form shown in the drawings, 1 indicates numeral keys and 2 character keys, which are mounted on key-levers 3, arranged to rock bell-crank 4 and thus swing type-bars 5 up rearwardly against the front side of a platen 6, mounted to rotate on a carriage 7. The carriage 7 has a step-by-step movement controlled at the actuation of each of the numeral keys by an escapement mechanism indicated in general at 8. This escapement mechanism includes a rack bar 9, movably mounted on the carriage 7 by means of a pair of arms 10 pivoted to the carriage. The rack bar 9 meshes detachably with a pinion 11 mounted on the same shaft as a ratchet wheel 12, which is controlled in its movement by fixed and movable dogs 13, the latter being oscillated at the actuation of any

of the character or numeral keys by means of a universal bar 14, which in turn is actuated by a heel 15^a formed on each of the type-bars 5.

5 In addition to the step-by-step movement of the carriage 7, provision is made for a jump or tabulating movement. For this purpose, there are provided tabulating keys 15, mounted on key-levers 16, which are 10 pivoted intermediate their ends and support thrust bars or plungers 17 at their rear ends. These thrust bars 17 are arranged to be projected by their associated keys into the path of tappets or stops 18, adjustably mounted 15 on a rack 19 carried by the carriage 7. When any one of the tabulating keys 15 is depressed and thus when any one of the plungers 17 is raised, the carriage 7 will be disconnected from the escapement mechanism 20 8 by means of a universal lever 20, which engages in a series of notches 21 provided in the plungers 17. This lever 20 when rocked by one of the plungers 17, pulls down on a link 22, which rocks a lever 23 carrying at 25 its front end a roller 24, which is arranged to lift the rack bar 9 out of mesh with the pinion 11.

In addition to actuating the type action of the type-writing mechanism, the numeral keys 1 are arranged to control a pin-setting mechanism indicated in general at 25, which sets pins 26 mounted on a series of bars 27, which are provided at their front ends with racks 28 engaging with pinions 29 for dial 35 or computing wheels 30 having numbers on their peripheries arranged to be exhibited through a sight opening 31 in the casing 32 of the computing mechanism.

In order that any one of the pins 26 on the bars 27 may be set, the bar carrying the pin must be raised above its fellows, as the pin-setting mechanism 25 has but a limited sphere of action. For this purpose, there is provided on the carriage, a tappet 33, which 45 during a traveling movement of the carriage, comes successively into engagement with individuals of a series of jacks 34, one for each of the computing wheels 30. These jacks are pivoted intermediate their ends, so 50 that when engaged by the tappet 33, they will be rocked to depress thrust links 35, which are connected to transposition linkages 36, which in turn raise the rack bars 27. The linkages 36 invert the order of action of 55 the rack bars 27 from that of the jacks 34, so that the progressive movement of the carriage which travels from right to left, may correspond to the progressive action of the computing which travels from left to right 60 of the computing wheels 30.

The pin-setting mechanism 25 not only sets the pins 26 for addition but is also capable of setting them for subtraction. The particular arrangement and action of the 65 pin-setting mechanism will now be described.

Referring to Figs. 1, 13 and 14, it will be seen that each of the numeral keys 1 is provided with a thrust link 37, which is arranged to engage an arm 38 on a rock shaft 39, there being one of these arms and one of these rock shafts for each of the numeral keys from "1" to "9".

Mounted on the shafts 39, there are provided addition arms 1^A, 2^A, 3^A, 4^A, 5AS, 6^A, 7^A, 8^A and 9^A. Each of these arms is arranged to engage, when the associated arm 38 is depressed, with the corresponding one of a series of wrist-pins 1^W, 2^W, 3^W, 4^W, 5^W, 6^W, 7^W, 8^W and 9^W on a series of pin-setting linkages 1^L, 2^L, 3^L, 4^L, 5^L, 6^L, 7^L, 8^L and 9^L. Each of these linkages, as will be seen by reference to Fig. 14, comprises an upper reach 40 and a lower reach 41 parallel to the upper reach 40 and connected thereto by a pair of bell crank levers 42 and 43, so that the motion of the reaches 40 and 41 will always be parallel. These linkages are held normally in close collapse with the lower reach 41 raised, by means of one or more springs 44. When, however, one of the rock shafts 39 is rotated 90 by the engagement of one of the plungers 37 with the associated arm 38, then the lower reach 41 will be depressed to engage the opposite pin 26 on the particular bar 27 which happens to be raised by the action of the tappet 33 engaging one of the jacks 34. That is to say, the pin corresponding to the particular numeral key struck will be set on the particular denominational column corresponding to the denominational column being written in on the work-sheet on the platen.

As shown in Fig. 13, the parts are in position for an adding operation. If it is desired to perform a subtracting action by the complementary method, then the parts are moved from the position shown in Fig. 13 to the position shown in Fig. 19. That is to say, all of the rock shafts 39 are mounted to slide in a frame 45 and can be shifted from the Fig. 13 position to the Fig. 19 position, to remove all of the arms 1^A, 2^A, 3^A, 4^A, 5AS, 6^A, 7^A, 8^A and 9^A out of engagement with the wrist pins 1^W, 2^W, 3^W, 4^W, 5^W, 6^W, 7^W, 8^W and 9^W at the same time moving a series of arms 1^S, 2^S, 3^S, 4^S, 5AS, 6^S, 7^S and 8^S into engagement with wrist pins 1^P, 2^P, 3^P, 4^P, 5^P, 6^P, 7^P and 8^P on the pin-setting linkages 8^L, 7^L, 6^L, 5^L, 4^L, 3^L, 2^L and 1^L, respectively. The arms 1^S, 2^S, 3^S, 4^S, 5AS, 6^S, 7^S, and 8^S are on the shafts 39 which correspond to their number and the number of the numeral key which actuates these shafts. It will be noted in passing that the arm 5AS corresponding to the numeral key 5, is used for both addition and subtraction, inasmuch as it lies between the 5^L and 4^L linkages which correspond to the adding of five and the subtracting of five, respectively. There is no subtraction arm provided for the "9" set, as the complement of nine is zero in this system.

In addition to the arms just mentioned, the shaft 39 corresponding to the "9" numeral key carries a restoring arm indicated at 9^R, which at the shifting of the rock shafts in the frame 35, is brought into engagement with a wrist RW on a "9" pin restoring linkage 9^{RL} acting similar to the other linkages except that it restores the "9" pins which have been previously set up when the "9" key is actuated in a subtracting action to subtract nine, as will be hereinafter described.

The shafts 39 and other co-operating mechanism may be shifted manually for the purpose of affording a subtracting relation of the computing mechanism. For this purpose, there may be provided a subtraction key 47 (Figs. 1, 4 and 18), which when pressed rearwardly against the tension of a spring 48, carries with it a subtraction rod 49. Mounted on the subtraction rod 49, there is a pin 50 engaging between the forks of an arm 51 secured to a rock shaft 52, so as to rock the same. Mounted on the rock shaft 52, there is also provided a fixed arm 53 and a loose arm 54 yieldingly connected together by a spring 55 and forming a forked space therebetween to engage a pin 57 projecting from a shifter bar 56, which is pivoted at the ends of its upper edge and engages in aligned slots 58 provided in each and all of the pin-setting rock shafts 39. The arms 53 and 54 are limited in their movements toward each other by a pin on the arm 53 and a toe on the arm 54. Normally, the arms 53 and 54 will move together so that when the subtraction key 47 is thrust rearwardly, it will swing the lower edge of the shifter bar 56 forwardly and thus shift all of the rock shafts 39 forwardly to a position such that the arms 1^A, 2^A, 3^A, 4^A, 5AS, 6^A, 7^A, 8^A and 9^A are shifted out of engagement with their wrist pins 1^W, 2^W, 3^W, 4^W, 5^W, 6^W, 7^W, 8^W, and 9^W, and at the same time the subtraction arms 1^S, 2^S, 3^S, 4^S, 5AS, 6^S, 7^S and 8^S are shifted into engagement with the corresponding wrist pins 1^P, 2^P, 3^P, 4^P, 5^P, 6^P, 7^P and 8^P. This shifting also brings the pin-restoring arm 9^R into engagement with the wrist pin RW on the pin-restoring linkage 9^{RL}. Such an action changes the pin-setting mechanism from a state in which it can set pins corresponding to the numeral keys actuated, to the opposite state in which it will set pins corresponding to the complements of the numeral keys struck, using one less than the exchange value, that is nine, as the base or complete number. If, however, the parts should jam and the subtraction arms 1^S, 2^S, 3^S, etc., should not properly engage with their pins 1^P, 2^P, 3^P, etc., then the free or loose arm 54 might remain behind while the spring 55 stretched, thereby preventing the breaking or jamming of any of the parts in case of such forcing.

In case the rock shafts 39 should be shifted only part way either backwardly or forwardly so as to be neither in their adding nor their subtracting position, means is provided to prevent an actuation of the pin-setting mechanism and also of the numeral keys. For this purpose, the arms 38 (Fig. 16) are provided with downwardly-projecting fins 38^D which barely clear upwardly-projecting fins 38^U on a stationary locking bar 38^L. The fins 38^D are so located with respect to the fins 38^U that when the rock shafts 39 are in an intermediate position corresponding to neither adding nor subtracting, then the fins 38^D will block a downward movement of the fins 38^U and thus prevent a downward movement of the arms 38 and a rocking of the shafts 39. Inasmuch as these arms 38 are rocked by the thrust rods 37 on the numeral keys 1, this will also prevent a complete downward movement of the numeral keys, advising the operative that the pin-setting mechanism is not properly adjusted, so that the trouble may be remedied.

As has been stated above, it is necessary at this time to set all of the "9" pins so that if no number is subtracted in any particular denominational column, the computing wheel will have a chance to rotate a complete revolution.

To set the "9" pins at the actuation of the subtraction key 47 (Figs. 1, 4, 18, 19 and 20), there is provided on the subtraction rod 49, a lug or extension 60, which engages the knuckle of a toggle 64, comprising links 65 and 66, so as to spread this toggle, forcing the free ends of the toggle apart so that the lower link 66 will rock an arm 67 mounted on a shaft 68 and connected to a universal U-shaped frame 69 underlying all of the pin-bars 27, so that this frame will be raised to raise all of the pin-bearing bars 27. Simultaneously with the raising of the pin-bearing bars 27, the upper link 65 of the toggle 64 will rock an arm 70, mounted on a shaft 71 and secured to a universal U-shaped frame 72, which overrides the lower reach of the 9^A linkage, so as to actuate the same to set all of the "9" pins. This universal U-shaped frame 72 is bent to avoid collision with the 9AS restoring linkage and thus permit actuation of each without interfering with the other.

It will thus be seen that simultaneously with the raising of the pin-bearing bars 27 by the spreading of the toggle 64, the same action will rock down the universal frame 72 against the tension of a spring 73, so that all of the "9" pins will be depressed from their raised position shown in Fig. 1 to their set position shown in Fig. 19, corresponding to nine-step movements of all of the pin-bearing rack bars 27.

At this time care is taken to provide also

for an extra step movement of the units or cents pin-bearing rack bar and its computing wheel. The extent of movement of the rack bars to rotate the associated computing wheels depends upon the particular pins set up thereon, as stated above. These pins are engaged by a cross bar 74 on a general operator 75, which is reciprocated in a manner to be described, so that on its forward motion it engages the set pins to force the pin-bearing rack bars forward an amount corresponding to the particular pins set up, and so that on its rearward motion it will return the rack bars by engagement with fixed lugs 76, one of which is provided on each of the rack bars.

As will be seen by reference to Figs. 22 and 23, the cross bar 74 of the general operator has a uniform front edge 77, except that portion which comes into engagement with the set pins on the units or cents bar indicated specifically at 78 in Fig. 22. That is to say, the general operator cross bar 74 has a piece 79 cut out of the front edge thereof, which piece can at times enter its socket 80, as in a normal adding operation, so that the units or cents pin-bearing rack bars will be given a movement corresponding to the particular pin set up thereon; or in other words, the front edge of the cut-out portion 79 will come into alignment with the front edge 77 of the body portion of the general operator cross bar 74.

For a subtracting operation, however, this cut-out portion 79 is located forward with its front edge one step in advance of the front edge 77 of the general operator cross bar 74, so that it will come into contact with whatever pin happens to be set on the units or cents bar 78 one step prior to the engagement of the front edge 77 with the corresponding pin on any of the other pin-bearing rack bars. To maintain this forward placement of the cut-out portion 79, there is provided a supernumerary bar 81 corresponding to the other pin-bearing rack bars 27, with the exception that it is unprovided with a rack in that it does not rotate any computing wheel directly and unprovided with pins. This supernumerary bar 81, however, carries the cut-out portion 79, so that it will reciprocate with the general operator cross bar 74.

In the normal adding operation, the cut-out portion 79 will be overtaken by the general operator cross bar 74 before the front edge 77 comes into engagement with any of the set pins on the pin-bearing rack bars, at which time the front edge of the cut-out portion 79 will be located in alignment with the front edge of the cross bar 74, so that all the pin-bearing rack bars will be given movements corresponding exactly to the pins set up thereon. At the end of the forward

stroke of the general operator cross bar 74, a lug 82 on the supernumerary bar 81, corresponding to the lug 76 on the pin-bearing bars, will be located one step to the rear of the bar 74, so that on the return movement of the latter the supernumerary bar 81 and the portion 79 carried thereby will lag behind the cross bar 74 one step, until the latter overtakes it, whereby when the general operator cross bar 74 comes to its home position, the front edge of the cut-out portion 79 will be located one step in advance of the front edge 77 of the cross bar 74.

As stated above, in the subtracting operation it is necessary to maintain the cut-out portion 79 in its advanced position with respect to the general operator cross bar 74. For this purpose, when the "9" pins are set up by the universal frame 72, a trigger 83 pivotally mounted on the supernumerary bar 81 is forced down from a raised position out of the path of the general operator cross bar 74, to a depressed position with a shoulder 84 thereon in the path of the front edge 77 of the general operator cross bar 74, by the engagement of the "9" pin setting linkage 94 with an upwardly-extending finger 85 on the trigger 83. The trigger 83 is held in its two positions of adjustment by a yielding detent 86 having a spring arm 87 which forces a ball or roller 88 alternatively into either one of a pair of sockets 89 and 90 provided in the trigger 83. That is to say, the ball 88 is located in an opening in the supernumerary bar 81 and is engaged on one side by the spring arm 87 and on the other side by the trigger 83, and when one of the sockets 89, 90 comes into register therewith, the ball drops into the socket and holds the trigger 83 in the particular position of adjustment corresponding to the registering of the particular socket with the ball. The up and down movements of the trigger 83 are limited, respectively, by lugs 91 and 92, which overhang the top edge of the supernumerary bar 81 at opposite sides of the pivot of the trigger 83.

It will thus be seen that when the "9" pins are set up for a subtracting operation, the trigger 83 will at the same time be depressed to bring its shoulder 84 into the path of the general operator cross bar 74, so that the front edge of the cut-out portion 79 carried by the supernumerary bar 81 will be maintained one step in advance of the front edge 77 of the general operator cross bar 74, whereby it will come into engagement with the particular pin which happens to be set up on the units or cents bar 78 one step in advance of the corresponding engagement of the front edge 77 with a corresponding pin set up on any of the other pin-bearing rack bars 27. This, then, gives to the units or cents wheel a

rotation one step in excess of that which it would receive to correspond with the particular pin set up on its associated rack bar. For example, if zero were subtracted in the 5 cents or units column, then the "9" pin would remain set up and the units or cents wheel would receive a rotation not only of nine steps but one step in excess thereof, so that it would be revolved ten steps or, a complete 10 revolution in this decimal system, whereby one would be carried to the next higher computing wheel.

After these actions have been accomplished, the subtraction bar 49 approaches the end of its motion when it is locked in its set position by a dog 93 engaging a notch 94^a in the subtraction bar 49, as in Fig. 2. Before the subtraction bar 49, however, has entirely completed its rearward 20 movement, the toggle 64 is permitted to collapse from its Fig. 19 position to its Figs. 2 and 4 position, so as to remove the universal pin-setting frame 72 and the pin-bar-raising frame 69 out of engagement with the 25 part subservient thereto, so as to permit the pin-bars to drop to their normal position, and raise the "9" pin-setting frame 72 clear of the "9" pin-setting linkage 95. To accomplish this, the lug or projection 62, 30 which engages the knuckle of the toggle 64, is adjustably mounted on the subtraction rod 49 to admit of its having a relative movement toward the front with respect to this rod. For this purpose, the toggle-spreading projection 63 is secured to a slide 35 94 having a pin-and-slot connection 95 with the subtraction key rod 49 (Figs. 1, 2, 18 and 19).

The slide 94 bearing the lug 62, is normally held in its rearmost position by a latch 96 pivotally mounted at 97 on the subtraction rod 49, and engaging a shoulder 98 provided on the slide 94. The latch 96 is also provided with an upstanding finger or 45 arm 99, arranged to engage, during the final rearward movement of the subtraction rod 49, with an adjustable stop or trigger 100 located in the path of movement of the finger 99. This stop or trigger 100 is shown 50 in the form of a screw adjustably mounted on a fixed bracket 101, so that the instant of its action can be varied to a nicety. When the finger 99 engages the trigger 100, the nose of the latch 96 is drawn out of engagement with the shoulder 98, so that the 55 spring 73 is free to act collapsing the toggle 64 from the position shown in Fig. 19 to the position shown in Fig. 2, forcing the slide 94 forwardly, raising the universal "9" pin-setting frame 72 out of engagement with the "9" pin linkage 95 and also depressing the rack-bar-raising frame 69 from the position shown in Fig. 19 to the 60 position shown in Fig. 1, whereby the pin-bars will assume a normal position ready to

receive the accumulation of the number to be subtracted.

On a subsequent return movement of the subtraction key rod 49 under the tension of the spring 48, when the subtraction key rod 49 is released by a movement of the dog 93 out of the notch 94^a, then the slide 94 will return to its rearward position with respect to the subtraction key rod 49 by being held against forward movement by engaging 75 with a stationary finger 102, extending downwardly from the frame 45 into the path of a shoulder on the slide 94. The latch 96 will be returned against the tension of a spring 103 thereon by a cam surface 80 104 on the slide 94, until it reaches a position such that the nose thereof will drop back into engagement with the shoulder 98 on the slide 94 when the slide will once more be locked in its rearmost position on the subtraction key rod 49.

At this point the mechanism is in condition to receive the setting-up pins corresponding to the digits of a number to be subtracted. That is to say, the numerical keys 1 may now be operated so that the digits of the number to be subtracted will be written on the work-sheet carried by the plate 6 and set up in the computing mechanism. The rack bars 27 will be raised 95 *simultaneously*, owing to the trigger 96 rocking the jacks 64 successively, which in turn raises the rack bars 27 *simultaneously* above their setting. As each numeral key is struck, the thrust rod 37 depending therefrom, will 100 rock the associated rack shaft 38, so as to actuate the connected pin-setting linkage, which is now connected for subtraction instead of addition, whereby the pin corresponding to the complement of the particular numeral key actuated, using nine as the base, will be set up with the setting-up of a pin for subtraction or with the striking of any of the numeral keys from "1" to "9" on the associated rack bar. For this purpose, there is provided on each rack bar 37, 110 a pin-restoring bar 43, pivoted at one end, as at 43^a, to the rack bar, and at the other end, as at 43^b, to a "0" pin actuating lever 50 on the opposite side thereof to that side 115 which is connected to the "9" pin. The lever 50 engages in a groove provided in the associated "9" pin. This "9" pin pin-restoring bar 43 has a notch 43^c extending parallelly to and in substantial alignment 120 with the tops of all of the pins from "0" to "9". The bar 43 dips downward at 43^a to avoid being engaged by the 95 linkage when the latter is actuated to set up after the "9" pins and extends upwardly to a point 43^b where it underlies the "0" pin pin-restoring linkage 66, which is actuated, when the "0" key is struck in a subtracting operation, to subtract nine; the lever 50 having provided with a dip in vertical alignment

ment with the 9^{RL} linkage so as to permit an upward movement of this lever simultaneously with a downward movement of the "9" pin restoring linkage 9^{RL}. It will thus be seen that when any numeral key from "1" to "9" in a subtracting operation is struck, the "9" pin will be restored and will only remain set up when no numeral key or the cipher key is struck in a column corresponding to the particular bar 27 in action.

This operation is continued for each decimal column until the entire number to be subtracted is accumulated by the setting-up 15 of complementary pins on the pin-bearing rack bars. The machine is then in condition for an actuation of the general operator 75, which on its forward movement will engage all of the set pins and thus rotate all 20 the computing wheels one complete revolution less the digits of the corresponding keys actuated, or, in other words, rotate them forwardly an amount corresponding to the complements of the numeral keys actuated, 25 with the exception of the units or cents wheel, which is rotated one step in excess of the complement accumulated therefor.

In case the "9" key should happen to be struck in the units or cents column in a subtracting operation, then the "9" pin would be unset and no other pin set up on the corresponding rack bar. In order, under such circumstances, to give the units or cents bar an added step movement, a downwardly-extending lug 300 is provided on the units or cents bar 78 in a position one step in advance of the "1" pin, whereby the extension or cut-out portion 79 will come into engagement therewith during the forward movement 40 of the general operator in subtracting and advance the units or cents rack bar and the associated dial wheel one step.

In considering the means for driving the general operator it will first be shown how 45 this can be controlled manually. At the front of the machine, there is provided a key 105^a (Figs. 4 and 40) mounted on a stem 106 having a vertical up-and-down play limited by a pin-and-slot arrangement 107. By 50 depressing the key 105^a against the tension of a spring 108, a lever 109 is rocked about its pivot 110, so that it in turn rocks a lever 111 which it overlies and engages at 112. The lever 111 is pivoted intermediate its 55 ends and in turn raises a stop pin 113, between two collars 114 and 115 of which it engages.

The stop pin 113 is normally held in a depressed position by a spring 116, (Fig. 4) 60 so that it lies in the path of a lug 117 on a clutch shifter 118. The pin 113 normally holds the clutch shifter 118 against the tension of a spring 119 in a position such that a friction roller or ball 120 will be in its ineffective position. That is to say, the spring

119 normally tends to throw the friction roller or ball 120 into such a position that it will form a clutch connection between a sleeve 121 and a hub 122, by the roller 120 being jammed between the sleeve 121 and the hub 122. For this purpose, the sleeve 121 is provided with a cam socket 123, which tapers from a deep portion at one end to a shallow portion at the opposite end.

When the roller 120 is in the shallow portion of the socket 123 as urged by the spring 119, it forms a clutch connection between the sleeve 121 and the hub 122, Fig. 41. When it is in the deep portion of this socket, as determined by the pin 113 obstructing the movement of the shifter 118 under the propulsion of the spring 119, then the sleeve 121 and the hub 122 are freed from connection with each other. This clutch connection forms a means of joining the general operator in driving relation with any form of motor, indicated by the electric motor 124. That is to say, the hub 122 is secured to a worm wheel 125, which is driven by a worm 126 mounted on a shaft 127, 90 which also forms a motor shaft for the motor 124.

The other element of the clutch, to wit, the sleeve 121, is secured to a shaft 128 (Figs. 38 and 39) which extends loosely 95 through the worm wheel 125 and is provided at its opposite end with a crank 129 carrying a cross head 130, which lies in a guide-way 131 provided in a reciprocating slide 132. The slide 132 is provided with an up-standing arm 133, arranged to engage at its head in a socket 134 secured in any suitable manner to the general operator 75.

It will thus be seen that when the pin 113 is raised from the Fig. 40 position to the Fig. 41 position, the spring 119 is free to rotate the clutch shifter 118, so as to bring the friction roller 120 from the deep portion of the socket 123 to the shallow portion thereof, forming a positive connection between the sleeve 121 and the hub 122, such that the arm 133 will be oscillated by the rotation of the motor 124, thereby giving the general operator 75 one complete cycle of movements, that is to say, a back-and-forth 115 sliding motion.

The clutch connection, however, is of the single-acting type, so that the general operator will be given but one cycle of movements. That is to say, the pin 113 is returned by the spring 116 to its normal depressed position as soon as pressure is released on the key 105^a or any other actuated part, so that it once more lies in the path of the lug 117, whereby when this lug comes 125 around at the completion of a single rotation of the shaft 128 with the worm wheel 125, then the clutch shifter 118 will be held stationary while the sleeve 121 and the hub 122 travel on slightly to bring the clutching 130

roller 120 back against the tension of the spring 119, into the deep portion of the socket 123, thereby interrupting the connection between the hub 122 and the sleeve 121.

5 The general operator 75 in addition to oscillating the pin-bearing rack bars 27 different amounts according to the pins set up thereon, also actuates other mechanism necessary at this time, such as the tens-carrying mechanism indicated in general at 135. This tens-carrying mechanism acts in the usual way, as illustrated in the Hanson application above mentioned, on the return stroke of the general operator and may be 15 driven in any suitable manner from the general operator as by means of gearing indicated in general at 136.

Inasmuch as it is desirable to return the subtraction key and other connected mechanism to their normal position after a subtracting operation has been completed, use is made of the movement of the general operator, in accumulating a computation, to release the subtraction key and permit the 20 spring 48 to return the subtraction key and the subtraction rod 49 to normal position. For this purpose, there is provided in one element of the general operator 75, to wit, one of the side bars, a cam socket 136, in which 25 normally rests a cam follower head 137 on a tripping lever 138. When the general operator starts its forward movement, one of the sides of the socket 136 engages the head 137 and rocks the lever 138 to rock a shaft 138a, so that an arm 139 thereon engages a pin 140 on an arm 141 of the dog 93 (Figs. 1 and 19). The dog 93 is then moved to disengaged position, permitting the spring 48 to return the key 47 and the subtraction rod 49 30 to normal ineffective position.

Among other functions the general operator 75 on its return stroke restores all of the set pins 26 to their normal raised position, so that they will be ready to accumulate a subsequent computation. For 35 this purpose, there is provided on the general operator, a pawl 142 which is pivoted so as to swing idly past an arm 143 on a rock shaft 144 during the forward motion 40 of the general operator. A spring 145, however, returns this pawl 142 to its normal position, so that on the return stroke of the general operator, the pawl 142 will act as a cam and swing the arm 143 upwardly; 45 thereby rocking the shaft 144 and an arm 146 to engage and raise a pin-restoring plate 147, which will raise all of the set pins 26. The pin-restoring plate 147 is supported for 50 parallel motion by means of two pairs of bell-crank levers 148, connected for parallel motion by one or more links 149.

The pin-restoring plate not only returns 55 the set pins 26 but also engages a downwardly-projecting lug 150 (Fig. 23) on the trigger 83, which provides for an extra step

movement of the units or cents computing wheel through the intermediary of the super-numerary bar 81, whereby the trigger 83, which if the previous operation was a subtracting one, will be returned to its normal 70 uppermost position corresponding to the removal of the shoulder 84 from the path of the general operator cross bar 74, whereby the movement of the super-numerary bar 81 will no longer be one step in advance of the 75 general operator cross bar 74.

It is desirable in this type of machine to enable the connecting up of the general operator with the motor automatically, so that the numbers can be run up in the computing head after the digits thereof have been accumulated. For this purpose, use is made of the stops or tappets 18, which in addition to locating the position of the carriage 7 for any desired column or even a 80 letter-space, may or may not be used to control the connection of the motor to the general operator.

If it is desired to connect up the general operator to the motor at any point in the 85 travel of the carriage, such as subsequent to the accumulation of a number to be computed by a setting-up of the computing pins, and subsequent to the writing of this number on the work-sheet carried by the platen, 90 then a stop 18 of the form shown in Fig. 12 will be located on the rack 19 at such point. This tappet or stop 18 during a movement of the carriage in a step-by-step or letter feeding direction, will engage a trip 157 100 (Figs. 4, 9 and 10), so as to depress the end of the same, which trip when depressed at one end will raise at its other end to pull on a link 158, so as to rock a U-shaped bail 159 forming a bell-crank lever and pivotally 105 mounted on a stub shaft 160. The other arm 161 of this bail 159 is connected to a latch 162 slidably mounted in a slot 163 and limited in its motion by the flange of a screw 164 entering a groove 165 therein. 110 The latch 162 is normally located in the position shown in Fig. 4, projecting above one end of an actuating lever 166 (Fig. 4). When the trip 157 is rocked by one of the tappets 18, it withdraws the latch 162 from 115 its position in the path of the lever 166, so that a spring 167 connected to this lever is free to raise the rear end thereof (Fig. 4), so as to force downwardly the front end thereof, whereby a pin 168, with which the 120 front end of the lever 166 engages, will be forced down to carry with it a thrust rod 169 on which the pin is mounted.

The rod 169 has a limited vertical movement determined by a pin-and-slot mounting 125 170, and is forked at its lower end to rest on the tripping lever 111, so that when the thrust rod 169 is depressed at the actuation of the motor trip 157 by one of the tappets 18, the tripping lever 111 will be rocked 130

able casing 207. As soon as the latch 200 is pulled down it releases the disk 204 and thus permits the shaft 205 to rotate under the tension of the spring motor 203. The shaft 205 carries thereon (Fig. 36) a gravity cam 208, which is normally located in the position shown in Fig. 36, so that as it rotates it swings the cam with it causing the latter to force rearwardly a cam follower 209 mounted on an arm 210 secured to the subtraction rod 49.

As has been stated above, the rearward motion of the subtraction rod 49 actuates the universal frames 69 and 72, to enable the setting of the "9" pins, the setting of the trigger on the supernumerary bar, and also the shifting of the rock shafts 89 from their addition to their subtraction setting position. It will thus be seen that this provides an automatic means for setting the mechanism for subtraction, which action occurs at the entrance of the carriage into the computing zone.

The arm 210 is pivoted to the subtraction rod 49 and held in position by a spring 211, with a toe 212 in engagement with a stop 213, so as to permit a return rotation of the shaft 205 and the cam 208 without a corresponding movement of the subtraction rod 49. The subtraction rod 49 extends around the shaft 205, so as to be guided thereby in its back-and-forth motion under the drive of the cam 208.

For the purpose of limiting the initial rotation of the shaft 205 and the cam 208, there is provided a stop 214 (Fig. 31), which is formed somewhat like the cam 208 and is arranged to engage a fixed stop block 215 having a curved socket to receive this stop 214 gradually.

It will be noted that the locking disk 204 is provided with a cam edge 216 to engage the upper arm 193 of the releaser 194, which is offset to come into the plane of the disk 204, whereby the arm 193 will be cammed away from the shaft 205 and thus the arm 193 raised against the tension of the spring 199, so as to enable the latch 191 to enter beneath the arm 193 and hold it in its non-releasing position. This will occur before the disk 204 returns to its initial position, as the general operator which indirectly returns it will not be actuated until the computing zone has been passed.

In order to prevent a racing of the motor 203 and the shaft 205 when released by the disengagement of the latch 200 from the disk 204, there is provided a retarder or governor 218 on the shaft 205 (Figs. 4, 34 and 35). This retarder consists of a gear 219 provided on the shaft 205 and engaging a rack 220 connected to a piston 221 working in a cylinder 222. The cylinder is provided with one or more outlet air holes 223, which may be plugged up individually by screw plugs 224.

As shown in Fig. 37, only the initial or outlet nearest to the right is open and the others are closed.

It will readily be seen that as the shaft 205 rotates, it will force the piston 221 from the position shown in Fig. 34 to the position shown in Fig. 35, and after passing the openings which happen to be free, the air will be entrapped between the cylinder head and the piston, forming a cushion which will retard the shaft 205 in its rotation, preventing the racing of the motor and the destruction of the parts. Of course if it is desired to vary the speed at which the shaft rotates, the number of the openings 223 which are left open, can be varied. These openings are different in size, so that a very nice adjustment of the retarder can be obtained.

For the purpose of retensioning the spring motor 203 and returning the locking disk 204 to its normal position and likewise returning the cam 208 to its normal ineffective position, use is made of the forward movement of the general operator in running up in the computing wheels the accumulated subtraction computation. To accomplish this, one of the side bars of the general operator is provided with a rack 266, which is engaged by a gear 267 meshing with a gear 268, which in turn drives a gear 269 loosely mounted on the shaft 205 but capable of being clutched thereto.

In order to connect the gear 269 in driving relation with the shaft 205, there is provided in the gear 269 a socket 270 (Figs. 21 to 28 inclusive), which is arranged to engage a clutching element 271 solely when the shaft 205 has had an initial rotation under the urgency of the spring motor 203, and thus when it is necessary to retension the spring 105 motor 203 and return the parts carried by the shaft 205 to their initial starting position. The clutching element 271 is normally held in its reared position in the socket 270 provided in the shaft 205 against the tension of a spring 272, which tends to throw it out.

When the shaft 205 has not been rotated and no subtraction-setting operation has taken place, then the gear 269 will oscillate idly back and forth under the drive of the general operator rack bar 263, without being connected positively to the shaft 205 by the clutching elements 270, 271.

When the shaft 205 and the clutching element 271 occupy the position shown in Fig. 23 corresponding to the termination of the initial rotation of the shaft in effecting a subtracting operation, then the clutch socket 270 is in register with the clutching element 271, which is projected by its spring out into this socket, so that during the forward motion of the general operator, the gear 269, which is rotated in a clockwise direction, as in Fig. 20, will carry the shaft 105

205 around with it, retensioning the spring 206 and bringing the parts carried by the shaft 205 back to their home starting positions. When this rotation is finished, which 5 occurs at the end of the forward stroke of the general operator, then the latch 200 will spring into the notch 203 provided in the disk 204 and lock the parts in their normal positions.

10 If it should be desired to throw the subtraction-setting mechanism out of operation, the releaser 194 may be held in its ineffective raised position. Then even if the tappet 33 carrying one of the subtraction dogs 174 should be raised to rock the universal frame including the rail 176 and thus release the latch 191, there would be no subtraction setting. To do this, there is provided on the releaser 194, a pin 273, which can be engaged 15 by a manually shiftable locking lever 274, which is provided with a hook toe to underlie the pin 273 and hold the releaser 194 in its raised position, irrespective of any action 20 of the subtraction trip mechanism controlled 25 from the carriage.

It may not always be desired to subtract, or even actuate the computing mechanism when a tappet 33 with the subtraction dog 174 thereon is in a computing zone in register 30 with the rail 176.

The mechanism so far has been described as if the tappet 33 and the dog 174 thereon were always in an effective position. As a matter of fact, they are never in an effective 35 position except when in a computing zone and not then if not desired. For this purpose, a tappet 33 (Figs. 6 and 42), of which there may be one or more, is mounted on rails 225 and 226. The rail 225 forms a supporting rail about which the tappet 33 may pivot from a lowered ineffective position to a raised effective position. The forward end of the tappet 33 may be supported by the rail 226 resting thereon and locked in any 40 adjusted position along the rails 225, 226, by a tooth 227 engaging in notches 228 provided at letter-space intervals along the rail 226. The tappet 33 is not positively connected to the rail 226 against up and down 45 movement and may be readily disconnected therefrom by raising it above the same. On the other hand, the tappet 33 is detachably secured from removal with respect to the rail 225, although it can pivot relatively 50 thereto. For this purpose, the tappet 33 is provided with a U-shaped socket 229, having legs extending on opposite sides of the rail 225, one end of the U-shaped socket being open to permit the detachment of the 55 tappet 33 from the rail 225. The tappet 33, however, is locked on the rail 225 by a hook-shaped catch 230, which is pivoted at 60 231 by means of a pair of arms extending on opposite sides of the tappet 33, and is provided with a guard 232 extending over

the opening of the U-shaped socket and engaging the rail 225. The catch 230 is normally held in the position shown in Fig. 6, by means of a spring 233, but may be raised by means of a finger-grip 234 to permit the 70 removal of the tappet 33 from the rail 225.

In order to remove the tappet 33, it must be swung about the rail 225; first, in order to disengage the tappet from the rail 225, and, second, in order to bring a nib 235 out 75 of engagement with one of a series of grooves 236 provided in the rail 225 at letter-space intervals. These grooves 236 extend into a common groove 237, which extends longitudinally of the rail 225, so that 80 when the tappet 33 is swung to its raised position, it can be readily moved longitudinally of the rail 225 but is locked in all other positions against such movement. It will thus be seen that when the tappet 33 is 85 raised to a substantially vertical position and the guard 232 moved from in front of the rail 225 by pressing on the finger-grip 234, the tappet 33 can be readily detached, and if desired to add instead of subtract, a 90 tappet similar thereto, with the exception that it is unprovided with a subtraction dog 174, may be put in its place. It will thus be seen that the tappets 33 of both the adding and subtracting types not only can be 95 adjusted along the length of the typewriter carriage but can be interchanged freely.

As has been stated above, the normal position of the tappets 33 is their lowermost one, or, in other words, their ineffective position. In order to raise the tappets 33 to their effective position when in a computing zone, there is provided on each tappet a following roller 238, which is arranged to engage a computing-zone-controlling roller 105 239, which is conical at both ends, so as to readily cam up the roller 238 and tappet 33 when the carriage moves, to bring the roller 238 into engagement with the zone-controlling roller 239. This zone-controlling roller 239 is of sufficient length to maintain the tappet in its raised effective position during the writing of digits of a number in a computing zone or column.

At this point it may be stated that the 115 tappet 33 in each instance is provided with a dog 240 having a camming edge to engage the denominational jacks 34 when the carriage is traveling in a letter-feeding direction and which is pivoted and held by a 120 spring 241, so as to yield during a return motion of the carriage.

The zone-controlling roller 239 may not, however, be always in a position such that it will raise the tappet 33 to an effective 125 position. In other words, the zone-controlling roller is supported by arms 242, mounted on a rock shaft 243, which may be rocked manually to an ineffective position by means of a handle 244 (Figs. 3, 8 and 42), 130

which thrusts the roller 239 out of its ineffective position against the tension of a spring 245. The handle 244 is connected by a thrust link 246 to a bell-crank lever 247, normally held in an ineffective position by a spring 248. The bell-crank lever 247 has a pin 249 underlying an arm 250 secured to the rock shaft 243. When it is desired to maintain the zone-controlling 5 roller 239 in its ineffective position by such manual control, the shank of the handle 244, which is shown in the form of a pin, may be passed to the extremity of a guiding L-slot 251, through which it extends and 10 is depressed in the short length of the slot, as at 252 in Fig. 3, so as to lock the thrust link 246 and thus the zone-controlling roller 239 against return movement.

It is also undesirable to have a subtraction-setting action take place while tabulating. To prevent this, the universal lever 20, which is rocked at the actuation of each and every tabulating key by engagement with the notches or ledges 21 on the plungers 17, 15 is fixed to a rock shaft 252, on which is also secured an arm 253, arranged to lift, by means of a pin-and-slot connection 254, a link 255 connected to swing upwardly an arm 256 secured to the rock shaft 243, thereby 20 by swinging the zone-controlling roller 239 to its ineffective position clear of the following roller 238.

In addition to this means of control, the zone-controlling roller 239 may be thrown 25 out so as to prevent a subtraction-setting operation when the general operator 75 is in motion, as otherwise a disruption of the mechanism might take place. For this purpose, the shaft 138°, which is rocked at the 30 initial forward movement of the general operator 75 by the cam socket 136 forcing the head 137 out on to the level of the side bar, is also provided with an arm 257 having a pin 258 arranged to engage an extension 35 259 on a thrust bar 260, which is guided for movement at one end by a pin-and-slot connection 261 and connected to rock, at its other end, a bell-crank 262. The bell-crank 262 is normally held in an ineffective position by a spring 263, but is rocked by the thrust bar 260, so that a pin 264 on the bell-crank will engage an arm 265 on the rock shaft 243, and thus swing the same upwardly to swing the zone-controlling roller 50 239 to its ineffective position.

It will be noted in passing that all of these controls, to wit, the manual control, the tabulating control, and the general operator control, which are used to render the 55 subtraction-setting tappet 33 ineffective by swinging the zone-controlling roller 239 to its ineffective position, have loose connections, so that one can be operated without disturbing the others.

60 In considering the operation of the de-

vice, the tappets 33 are arranged along the carriage 7 at points where it is desired to have computing zones or columns. Where it is desired to merely add, a tappet without the subtraction dog 174 is placed so as to 65 actuate the jacks 34 at the correct point in the travel of the carriage. Where, however, it is desired to have a subtracting operation take place, a tappet 33 is located on the carriage 7 with a subtraction dog 174, so that as 70 the carriage enters the column or zone in which it is desired to subtract, the dog 174 will trip the subtraction-setting mechanism to enable a subtracting operation.

After the tappets 33 for adding and subtracting have been arranged correctly on the carriage 7, then starting with the carriage at the extreme right, one of the tabulating keys 15 may be struck to move the carriage to the first computing zone or column. During any such tabulating movement the computing and subtraction-setting mechanism is rendered ineffective by reason of the fact that the universal lever 20 rocks the shaft 252, which in turn, through the connecting 75 linkage, rocks the shaft 243 to swing the zone-controlling roller 239 free and clear of the path of travel of the tappets 33, so that the latter will remain in their normal depressed ineffective position.

If we assume that this first computing zone is an adding zone, the numeral keys 1 may be then struck to actuate the pin-setting mechanism, so as to set the pins 26 on the bars 27, in accordance with the values of the 100 numeral keys actuated and in accordance with the columns as typewritten on the work-sheet on the carriage. This latter is rendered possible by the adding tappet 33 being raised to an effective position by the 105 zone-controlling roller 239, as the carriage enters the first computing zone.

When all the digits of the number to be added in the first computing zone have been accumulated by the setting of the pins 26, 110 then on a further movement of the carriage, one of the tappets or stops 18 of the form shown in Fig. 12, which has previously been properly set on the rack 19 on the carriage 7, will come into engagement with the trip 117 115 and rock the same, so as to withdraw the latch 162 permitting the rocking of the lever 166, so as to rock the lever 111 and withdraw the stop pin 113 from in front of the projection 117 on the clutch connector 118, 120 thereby enabling the automatic clutch between the motor and the general operator 75 to become effective, and thereby causing one complete cycle of movements of the general operator 75 including a back-and-forth 125 stroke. On the forward stroke, the accumulated digits will be run up in their accordant computing wheels 30, and on the return stroke the tens-carrying initiated by the computing wheels will be completed.

We will assume for the purpose of illustration, that the second column or zone is a subtracting one, so that a tappet 33 with one of the subtraction-setting dogs 174 will be 5 located on the carriage 7 for this zone. After the number added has thus been run up in the computing wheels, one of the tabulating keys 15 may be struck to bring the carriage 7 to this second computing zone or 10 column. As the carriage enters this subtraction-computing zone or column, the dog 174 on the tappet 33 will engage the universal shift rail 176 and rock the frame carrying the same, so as to thrust down the 15 link 185 and thus rock the shaft 187, which in turn, through the link 189 and the bell-crank 190, removes the latch 191 from a position supporting the latch-releaser 194, so that the spring 199 is free to rock the same, 20 and thus by engagement with the pin 201, enable the latch-releaser to withdraw the latch 200 from its position in the notch 203 provided in the disk 204 on the shaft 205. This, then, permits the shaft 205 to start to 25 rotate under the propulsion of the spring motor 206, which has been previously tensioned. The speed at which the shaft 205 and the parts carried thereby are rotated, will be controlled nicely by the retarder 30 218, so that there will be no racing and thus no abnormal jarring and wearing of the parts.

As the shaft 205 rotates, it carries the cam 208 around with it gradually forcing 35 the subtraction rod 49 rearwardly against the tension of the spring 48. As the subtraction rod 49 moves rearwardly, the extension or projection 63 carried thereby will engage the knuckle of the toggle 64, spreading 40 the toggle so as to rock upwardly the universal frame 69 to raise all of the pin-bearing rack bars 27 and also so as to concomitantly rock downwardly the universal frame 72, in order to depress the lower reach of 45 the 9^h pin-setting linkage. This, then, enables the setting of all of the "9" pins on the bars 27 and also the setting of the trigger 83 on the supernumerary bar 81, so as to provide for an extra step movement of the computing wheel of lowest denomination, that is, 50 the units or cents wheel in the present system.

In addition to setting the pins and trigger, the rearward movement of the subtraction 55 rod 49 also rocks the arm 51, so as to in turn actuate, through the yieldable safety connection, the shift bar 56, which in turn slides all of the rock shafts 39 forwardly to change from their connection to set according to addition, to their connection to set according to subtraction. That is to say, the adding arms 1^a, 2^a, 3^a, 4^a, 5as, 6^a, 7^a, 8^a and 9^a are shifted out of engagement with the pins on the linkages 1^l, 2^l, 3^l, 4^l, 5^l, 6^l, 65 7^l, 8^l and 9^l, and the arms 1^s, 2^s, 3^s, 4^s,

5as, 6^s, 7^s and 8^s are shifted, respectively, into engagement with the pins on the pin-setting linkages 8^l, 7^l, 6^l, 5^l, 4^l, 3^l, 2^l and 1^l, there being no arm for actuating one of the pin-setting linkages for the "9" key, as 70 the complement of nine in this decimal system, is zero. There is, however, another arm 9^h on the rock shaft 39 corresponding to the "9" key, which at this time is shifted into engagement with the pin RW on the restoring linkage 9^{RL}, which is effective to restore the "9" pins on any raised rack bar 27 when nine is subtracted in any particular denominational column.

If it should happen that through some derangement of the parts, the shafts 39 could not move fully forward, then in order to prevent the breaking of any of the elements, the parts of the safety connection including the fixed arm 54 and the loose arm 52, will 85 move relatively to each other, the spring 55 yielding to accommodate this movement. While this action prevents the breaking of any of the elements in the subtraction-setting mechanism, it might occur with such a partial shifting of the rock shafts 39, that none of the arms on these shafts would be in engagement with any of the pins on the pin-setting linkages, but with the parts of the subtraction-setting mechanism in such an abnormal state, the arms 38 on the rock shafts 39 would not be shifted to one of their extreme positions, and hence, the fins 38^a, shown in Fig. 16, would lie directly above the fins 38^b, so as to prevent the downward 90 movement of the arms 38 and thus prevent the rocking of the shafts 39 and the complete actuation of the keys 1. This, then, would warn the operative that the mechanism was out of order, and in fact prevent 95 him from setting up a computation.

Normally, however, the adjustment of the pin-setting mechanism 25 for subtraction would take place correctly without any jamming or other unintended results, so that 100 this pin-setting mechanism 25 would be in a condition to set up the pins 26 to correspond with the complements of the values of the numeral keys struck, using nine as the base or measure in obtaining the complement. 105

As the subtraction rod 49 approaches the rearmost limit of its stroke in setting up a subtraction condition, the latch 96 would come into engagement with the trip 100, releasing the slide 94, thereby permitting the collapse of the toggle 64 as a result of the constantly effective restoring effort or force exerted by the spring 73, so that the universal frames 69 and 72 will be withdrawn 110 from engagement with the parts actuated thereby. When the subtraction rod 49 reaches the extreme end of its throw, it is caught by the dog 93 and held in its set position until subsequently released on the move- 115 120 125 130

ment of the general operator in running up the subtraction computation which the mechanism is now in condition to accumulate. The numeral keys 1 would then be actuated to write the digits of the number to be subtracted, whereby the values of the digits would be correspondingly accumulated by a setting of the pins 26.

In striking any of the numeral keys from 10 "1" to "8" to set up the complementary pins 26, the pin-setting linkage thereof will come into engagement with the restoring link 46, as indicated in Fig. 21, so as to rock the "9" pin lever 59 and bring the "9" pin on the 15 particular bar up to its normal unset position. In case the "9" pin is struck, as in subtracting nine, inasmuch as the complement of nine is zero in this system, the "9" pin must also be unset under such circumstances. 20 The 9^{RL} linkage will then come into play, as it is connected to the shaft 39 corresponding to the "9" key, and will engage the shoulder 46^a on the pin-restoring link 46 and depress the same, so as to raise the "9" pin on 25 the particular denominational bar 27 corresponding to the striking of the "9" key.

After the entire number has been written and thus accumulated, one of the tappets 18 of the form shown in Fig. 12, which previously has been properly located on the rack 19 carried by the carriage 7, will engage the trip 157 to enable the clutch connection of the general operator in driven relation with the motor 124. As the general 30 operator moves forward, the cross bar 74 thereof will engage the set pins on all of the bars 27 with the exception of the units or cents rack bar, and will rotate the computing wheels 30 amounts corresponding to the complements of the numeral keys actuated. The units or cents wheel will be given an additional step of movement, however, owing to the cutout portion 79 engaging the pins set on the units rack bar 78 one step in advance 35 of the front edge 77 of the general operator cross bar 74, with corresponding set pins on the other rack bars.

During the forward movement of the general operator, the lever 138 will be rocked by the follower head 137, being cammed out of the socket 136, so as to rock the shaft 138^a, enabling the arm 139 to trip the dog 93, permitting the return of the subtraction rod 49 and the parts held in a subtraction-setting position thereby to a normal adding position. The rocking of the shaft 138^a also actuates the thrust link 260 to rock the bell crank 262 and thus rock the shaft 243, whereby the zone-controlling roller 239 will be swung rearwardly clear of the following roller 238 on whatever tappet 33 happens to be in the computing zone at that time, so that not only will a normal computing action be prevented but also a subtraction-setting will likewise be prevented during the

movement of the general operator 75. Also during the forward movement of the general operator 75, the train of gearing to the rack 263 carried by the general operator (Fig. 24) will rotate the shaft 266 clockwise, so as to retension the spring 260 and return the parts carried by the shaft 263 to their normal position, permitting the re-entrance of the latch 260 in the notch 262 to lock the parts in their normal set position. At the return of the general operator 75, tens will be carried between the courting wheels and the mechanism ready for a new computing operation.

This operation may be repeated as often as desired for as many columns or zones as the capacity of the carriage 7 will admit of writing. Then when the end of the type-written line is reached, the carriage may be returned and a new line of computation effected. During such return motion of the carriage, the dogs 174 and 240 will be rocked back and forth without affecting the parts normally actuated thereby when the carriage moves in a letter-feeding direction.

If it should be desired to disconnect the computing mechanism and the typewriting mechanism from each other, so that a typewriting operation may be carried on without a concomitant computing action, then the manual lever 244 can be shifted to the position shown in Fig. 3, wherein the zone-controlling roller 239 will be shifted rearwardly to its ineffective position and held there, so that all of the tappets 33 will remain in their lower ineffective position during the travel of the carriage. Under these circumstances, not only will the jacks 34 remain passive and thus prevent the setting of pins 26, but also the subtraction-setting mechanism will be free from control by the dogs 174.

Variations may be resorted to within the scope of the invention, and portions of the improvements may be used without others.

Having thus described my invention, I claim:

1. In a computing machine, in combination, a totalizer comprising a set of computing elements, operating mechanism for said totalizer including a set of variably settable indexing devices and setting mechanism therefor, by which may be effected a preliminary representation or set-up of a number to be computed, said operating mechanism also including means for completing a computation by causing said computing elements to be actuated in accordance with the setting of said indexing devices, means, including a traveling carriage and parts operated on movement thereof, for determining a computing zone, computation-state-setting mechanism for selectively varying the relations of parts of said index-setting mechanism, so that a preliminary rep-

- resentation or set-up of the indexing devices may be electively caused to be determinative of either an addition or a subtraction of the number to be computed, the normal 5 relation of the parts of said index-setting mechanism being such as to effect a setting determinative of a computation of one character and being variable so as to cause a setting determinative of a computation of 10 the other character, and means, including parts operated on movement of said carriage into said zone, for effecting an actuation of said state-setting mechanism so that a set-up by said index-setting mechanism, when 15 the carriage is in said zone, will be determinative of a computation of the character opposite to that which would be determined by the normal relation of parts of said index-setting mechanism.
- 20 2. The combination with a computing mechanism, of means for changing the character of computing action of said computing mechanism, a latch for said changing means, a releaser for said latch, a lock for said releaser, a carriage traveling to determine different computing zones or columns, means actuated directly from said carriage, as the same enters a zone to have a computing action different from the previous zone, for unlocking said releaser, and means for instantly actuating said releaser on being unlocked to release said latch and enable a change in state of said computing mechanism.
- 25 3. The combination with a computing mechanism, of a subtraction-setting mechanism for said computing mechanism, a series of jacks connected to said computing mechanism for controlling the denominational columns thereof, a traveling carriage, a tappet carried by said carriage, a one-way acting dog for operating said jacks one by one during the traveling movement of said carriage, connections to said subtraction-setting mechanism including a bar universal to the range of said jacks, and a dog carried by said tappet engaging said bar during a letter-feeding movement of said carriage to cause a subtraction-setting operation of said 30 computing mechanism during the period of actuation of said dogs.
- 35 4. The combination with a computing mechanism, of a subtraction-setting mechanism for said computing mechanism, a carriage traveling to determine different computing zones or columns, connections to said subtraction-setting mechanism to enable the actuation of the same, said connections including a bar universal to all of the letter 40 spaces of a computing zone, and a dog carried by said carriage to engage said bar during a computing zone so as to maintain said computing mechanism in a state for a subtracting action.
- 45 5. The combination with a computing

mechanism, of a subtraction-setting mechanism for said computing mechanism, a carriage traveling to determine different computing zones or columns, connections to said subtraction-setting mechanism to enable the 70 actuation of the same, said connections including a bar universal to all of the letter spaces of a computing zone, and a dog carried by said carriage to engage said bar while the carriage is in a computing zone so as 75 to maintain said computing mechanism in a state for a subtracting action, said dog being mounted to act solely during a movement of said carriage in a letter-feeding direction, and so as to be moved to an ineffective position by engagement with the end of said bar on a return movement of said carriage after a movement in letter-feeding direction such as to cause said dog to entirely clear said bar.

6. The combination with a computing 85 mechanism, of a subtraction-setting mechanism for said computing mechanism, a carriage traveling to determine different computing zones or columns, connections to said subtraction-setting mechanism to enable the 90 actuation of the same, said connections including a bar universal to all of the letter spaces of a computing zone, and a dog carried by said carriage to engage said bar during a computing zone so as to maintain said computing mechanism in a state of subtracting action, said dog being mounted to act solely during a movement of said carriage in a letter-feeding direction, said bar having a 95 notch therein to render said dog ineffective on the return movement of said carriage before said dog has entirely cleared said bar and after said dog has reached the termination of a computing zone or column.

7. The combination with a computing 105 mechanism, of a subtraction-setting mechanism for said computing mechanism, means for actuating said subtraction-setting mechanism, and means for controlling the action of said first-mentioned means, including a 110 latch, a bell crank actuating said latch, a linkage for actuating said bell crank, a pivotally-mounted frame having a bar extending the full length of a computing zone or column and a traveling dog arranged to cam 115 said bar so as to rock said frame.

8. The combination with a computing mechanism, of a subtraction-setting mechanism for said computing mechanism, driving 120 means for said subtraction-setting mechanism, a latch for preventing the action of said driving means, a releaser for said latch, a spring normally tending to move said releaser to its releasing position so as to withdraw said latch and permit an actuation of said subtraction-setting mechanism, a second latch for preventing the operation of said releaser, a traveling carriage, and means actuated from said carriage for manipulating 125 said second latch.

9. The combination with a computing mechanism, of a subtraction-setting mechanism for said computing mechanism, driving means for said subtraction-setting mechanism, a traveling carriage, a latch for preventing the action of said driving means, a releaser for said latch, a spring normally tending to actuate said releaser so as to actuate said latch, a second latch for said releaser, and a bar connected to said second latch and actuatable from said carriage so as to enable the operation of said releaser and maintain said second latch in its ineffective position during the entire width of a computing zone or column.

10. The combination with a computing mechanism, of a subtraction-setting mechanism for said computing mechanism, driving means for said subtraction setting mechanism, means for controlling the action of said driving means including a latch, a bell crank connected to said latch, a link connected to said bell crank, a rock shaft connected to said link, a frame having a bar universal to all the digits of a computing zone, connected to rock said rock shaft, and a traveling carriage for shifting said bar.

11. The combination with a computing mechanism, of a subtraction-setting mechanism for said computing mechanism, actuating means for said subtraction-setting mechanism, a latch for preventing the action of said actuating means, a releaser for said latch, means for returning said actuating means to its normal position after having operated said subtraction-setting mechanism, and a cam carried by said actuating means for restoring said releaser to its normal position.

12. The combination with a computing mechanism, of means for changing the character of actuation of said computing mechanism, an actuating mechanism for said changing means, a latch for preventing the operation of said actuating mechanism, a releaser for said latch, a spring for actuating said releaser, means for restoring said actuating mechanism to its normal condition after having actuated said changing means, and a cam carried by said actuating means and engaging said releaser for restoring said releaser to its normal position and acting to retension said spring.

13. The combination with a computing mechanism, of a subtraction-setting mechanism for said computing mechanism, actuating means for said subtraction-setting mechanism, a latch for controlling the operation of said actuating means, a releaser engaging said latch, and a spring operating said releaser to release said latch and permit the operation of said actuating means.

14. The combination with a computing mechanism, of a subtraction-setting mechanism for said computing mechanism, actuat-

ing means for said subtraction-setting mechanism, and a spiral stop for gradually bringing said actuating means to rest.

15. The combination with a computing mechanism, of a subtraction-setting mechanism for said computing mechanism, actuating means for said subtraction-setting mechanism, a cam stop carried by said actuating means, and a fixed block having a concave surface to engage said cam stop and slow up said actuating means gradually.

16. The combination with a computing mechanism, of a subtraction-setting mechanism for said computing mechanism, a shaft, means for rotating said shaft, a cam carried by said shaft for actuating said subtraction-setting mechanism, and a cam stop conforming in contour and position to said cam for determining the stopping point of said shaft.

17. The combination with a computing mechanism, of a subtraction-setting mechanism for said computing mechanism, a shaft for actuating said subtraction-setting mechanism, a notch disk on said shaft, a latch engaging the notch of said disk, and a releaser for said latch, said disk being cam-shaped and engaging said releaser to return it to a normal position after having actuated said latch.

18. The combination with a computing mechanism, of a subtraction-setting mechanism for said computing mechanism, a shaft for actuating said subtraction-setting mechanism, a disk carried by said shaft having a notch therein, a latch engaging said notch to lock said shaft against movement, and a releaser engaging said latch to bring the same to an ineffective position, said disk acting to return said releaser, said releaser and said latch being capable of relative bodily movement so as to admit of the return movement of said releaser before the return of said latch.

19. In a machine of the character described, the combination with a rail, of a computing tappet mounted on said rail, a latch for securing said tappet to said rail, a jack dog pivotally mounted on said tappet, and a second dog pivotally mounted on said tappet for controlling the character of computation.

20. In a machine of the character described, the combination with a rail, of a tappet adjustably mounted on said rail, a latch for holding said tappet on said rail, and a plurality of camming dogs pivotally mounted on said tappet and held against movement in one direction so as to effect a camming action when said tappet moves in one direction, said dogs being pivotally mounted so as to admit of the yielding of said dogs when said tappet moves in the opposite direction to that above mentioned.

21. In a machine of the character de-

scribed, the combination with a rail, of a tappet having a U-shaped socket therein to engage said rail, a latch pivotally mounted on said tappet and having a guard arranged to project across the open side of said socket so as to secure said tappet on said rail, a spring for maintaining said latch in its locking position, and a finger-piece on said latch for enabling the removal of said latch from 10 its locking position against the tension of said spring.

22. In a machine of the character described, the combination with a tappet, of a dog pivotally mounted on said tappet, and 15 a pin on said dog projecting to engage one side of said tappet to limit the movement of said dog.

23. In a machine of the character described, the combination with a tappet, of a 20 pin adjustably mounted in said tappet, a dog pivotally mounted on said pin, and spring yieldingly connecting said dog with said pin.

24. In a machine of the character described, the combination with a tappet, of a 25 pin adjustably mounted in said tappet, a dog pivotally mounted on said pin, a spring yieldingly connecting said dog with said pin, and means for holding said pin in any 30 adjusted position.

25. In a machine of the character described, the combination with a tappet, of a pin mounted on said tappet, a dog pivotally mounted on said pin, a spring connected 35 at one end to said dog and at the other end to said pin, and a second pin for limiting the movement of said dog in one direction.

26. In a machine of the character described, the combination with a tappet, of a 40 pin adjustably mounted on said tappet, means for locking said pin in any adjusted position, a dog pivotally mounted on said pin, a spring connected at one end to said dog 45 and at the other end to said pin, so as to permit a yielding movement of said dog relatively to said pin, and a second pin engaging the side of said tappet to limit the movement of said dog in one direction.

50 27. The combination with a series of computing jacks, of a computation-determining mechanism, a rail, a tappet pivotally mounted on said rail, a dog mounted on said tappet to actuate such jacks, a dog mounted 55 on said tappet to actuate said computation-determining mechanism, said tappet being normally located in a position such that said dogs will be ineffective to actuate the parts which they are intended to actuate, 60 and means for automatically raising said tappet to render both said dogs effective.

28. The combination with a computing mechanism, of a subtraction-setting mechanism for said computing mechanism including a subtraction rod, a shaft, a cam 65

mounted on said shaft, a follower on said subtraction rod arranged to be actuated by said cam during a rotation of said shaft, so as to bring into play said subtraction-setting mechanism, motive means for said 70 shaft, a cam stop on said shaft corresponding with said cam, and a fixed stop engageable by said cam stop to bring said shaft gradually to rest.

29. The combination with a computing mechanism, of a subtraction-setting mechanism for said computing mechanism including a subtraction rod, a follower on 75 said rod, a cam engaging said follower, a shaft for rotating said cam, a cam stop 80 conforming in contour to and register with said cam, and a concave fixed stop co-operating with said cam stop to bring said shaft to rest at the completion of the action of said cam.

85 30. The combination with a series of denominational members, of pins mounted on said members and settable to determine the extent of movement thereof, said pins ranging from lowest value to highest ultimate value for the particular exchange values between adjacent denominational members, a series of linkages, each capable of setting the pins of the same value on the different denominational members, numeral keys for actuating said linkages, and a special frame arranged to actuate the linkage for setting the pins of highest ultimate value independently of the action of said numeral keys, so as to predetermine the 90 movement of said members equivalent to their greatest possible movements.

95 31. The combination with a series of denominational members, of pins mounted on said members and settable to determine the extent of movement thereof, said pins ranging from lowest value to highest ultimate value for the particular exchange values between adjacent denominational members, a series of linkages each capable of setting 100 the pins of the same value on the different bars, numeral keys for actuating said linkages, a special frame arranged to actuate the linkage for setting the pins of highest ultimate value independently of the action of 105 said numeral keys so as to predetermine the movement of said denominational members equivalent to their greatest possible movements, and means for concomitantly lifting all of said denominational members at the 110 actuation of said frame to enable the setting of the pins of highest value.

115 32. The combination with a series of denominational bars, of nine pins on each of said bars settable to determine the extent of movement thereof, linkages individual to pins of the same values on the different bars, numeral keys ranged from "1" to "9" for actuating said linkages, and a special frame for actuating one of said linkages 120 125 130

for setting the "9" pins independently of the numeral key "9".

33. The combination with a series of denominational members, of pins settable on said members, to determine the extent of movement thereof, means for setting, preparatory to a subtracting operation, a series of said pins of the same value one on each of said members, linkages for setting said 10 pins individually, and a linkage movably mounted on each of said members and connected to said specially mentioned pins and arranged so as to be actuated by certain of said pin-setting linkages to unset said specially mentioned pins.

34. The combination with a bar, of pins on said bar settable to determine the extent of movement thereof, said pins ranging from highest ultimate value to lowest value corresponding to greatest and smallest possible movements of said bar, a lever connected to the pin of highest value, and a link pivotally connected to said bar and to said lever and having a reach extending adjacent to 25 and in alinement with the tops of said pins so as to be actuated at the setting of said pins to unset said pin of highest ultimate value.

35. The combination with a rack bar, of 30 a series of pins settable on said rack bars to determine the extent of movement thereof, said pins ranging from "1" to "9" corresponding to one to nine step movements of said bar, a lever connected to the "9" pin, and a link pivotally mounted on said bar at one end and pivoted to said lever at its opposite end and having a reach extending adjacent to and in substantial alinement with the tops of said pins so as to be 40 actuated at the setting of a pin less than the "9" pin to unset the "9" pin if previously set.

36. The combination with a rack bar, of 45 a series of pins settable on said rack bar to determine the extent of movement thereof, said pins ranging in values from "1" to "9" corresponding to one to nine step movements of said rack bar, a lever connected to the "9" pin, a link pivotally connected 50 to said lever and pivotally connected to said bar, said link having a reach extending in substantial alinement with the tops of the pins from "1" to "8" and having a dip therein in juxtaposition to the "9" pin, so 55 as to enable the unsetting of the "9" pin when any other pin than a "9" pin is set.

37. The combination with a pin-setting mechanism, of means for re-arranging said pin-setting mechanism to control the character of computation carried on thereby, and locking means for preventing the actuation of said pin-setting mechanism when, in an intermediate incorrect position.

38. The combination with a series of rock 60 shafts, of a series of linkages connected to

be actuated by said rock shafts, said linkages and said rock shafts having two possible ways of connection, shifting means for determining in what way said rock shafts shall be connected up to said linkages, and locking means for preventing the actuation of said rock shafts when the connection is interrupted between said rock shafts and said linkages.

39. In a computing machine having denominational pin-bars and pins mounted in settable relation with said bars, the combination with a series of rock shafts, of a series of pin-setting linkages, said rock shafts and said linkages having two possible ways of connection to determine whether the pins set by said linkages shall be set for addition or for subtraction, shifting means for varying the connection between said linkages and said rock shafts, an arm individual to each of said rock shafts, and locking fins arranged to interrupt the movements of said arms when said connection between said rock shafts and said linkages is interrupted.

40. The combination with a series of rock shafts, of a series of linkages, one individual to each of said rock shafts, said linkages and said rock shafts having two possible ways of connection corresponding to addition and subtraction, shifting means for controlling the connections between said rock shafts and said linkages, an arm on each of said rock shafts, a fin on each of said arms, and a series of locking fins disposed in the path of movement of said fins on said arms when said connections between said rock shafts and said linkages are interrupted or but partially connected.

41. The combination with a series of rock 105 shafts, of a series of linkages, one individual to each of said rock shafts, said rock shafts and said linkages having two possible ways of connection corresponding to addition and subtraction, shifting means for determining 110 the method of connecting said rock shafts with said linkages, arms on said rock shafts occupying two positions corresponding on the one hand to subtraction and on the other hand to addition, each of said arms having 115 a fin thereon, and a series of fixed fins located at a point intermediate the extremes of throw of said arms, so as to come into the path of said fins on said arms when said arms and the parts connected thereto 120 have been but partially thrown in changing between addition and subtraction in order to interrupt the movements of said arms and the parts connected thereto.

42. The combination with a series of rock 125 shafts, of a series of linkages, one individual to each of said rock shafts, said rock shafts and said linkages having two possible ways of connection corresponding to addition and subtraction, shifting means for determining 130

the method of connecting said rock shafts with said linkages, arms on said rock shafts occupying two positions corresponding on the one hand to subtraction and on the other hand to addition, each of said arms having a fin thereon, and a series of fixed fins located at a point intermediate the extremes of throw of said arms so as to come into the path of said fins on said arms when said arms and the parts connected thereto have been but partially thrown in changing between addition and subtraction in order to interrupt the movements of said arms and the parts connected thereto, said fins being thin enough to permit an action of said arms when said connection between said rock shafts and said linkages is perfect for either addition or subtraction.

43. In a computing machine, in combination, indexing mechanism having parts connectible in different relations determinative of computations of different character, an operating member through which said changes may be effected, computation-state-setting mechanism including a driver for said operating member, and a yieldable connection between said driver and said operating member, so that in case said indexing mechanism should become stalled during a setting operation, said state-setting mechanism may be permitted to complete its setting movement without damage to the machine.

44. The combination with a nest of pins, of a series of linkages for setting said pins, a series of rock shafts for actuating said linkages, each of said rock shafts having a plurality of arms capable of connecting said rock shafts with different ones of said linkages, a shift bar for adjusting said rock shafts to different positions, an arm connected to said shift bar, a spring connected to said last-mentioned arm, an arm connected to said spring, and a subtraction bar for manipulating said last-mentioned arm, said spring being arranged to yield on undue pressure for interference with the movement of said shift bar so as to prevent the breakage of the parts.

45. The combination with a nest of pins, of setting mechanism for said pins, said setting mechanism being adjustable to vary the character of setting action according to either addition or subtraction, a shift bar for adjusting said setting mechanism, an arm for actuating said shift bar, a spring tending to draw on said arm, a second arm connected to said spring to draw on the same, and a subtraction rod for manipulating said second-mentioned arm.

46. The combination with a nest of pins, of setting mechanism for said pins, said setting mechanism being adjustable to vary the character of setting action according to either addition or subtraction, a shift bar

for adjusting said setting mechanism, an arm for actuating said shift bar, a spring tending to draw on said arm, a second arm connected to said spring to draw on the same, a subtraction rod for manipulating said second-mentioned arm, and means for limiting the relative motions of said arms.

47. The combination with a nest of pins, of setting mechanism for said pins, a shift bar for adjusting said setting mechanism according to addition or subtraction, an arm connected to said shift bar, a spring tending to draw on said arm, and a bell crank for pulling on said spring.

48. The combination with a computing mechanism, of a subtraction-setting mechanism for said computing mechanism, a traveling carriage, connections for controlling the actions of said subtraction-setting mechanism from said carriage, a general operator for running up a computation effected by said computing mechanism, and means for interrupting the connections from said subtraction-setting mechanism to said carriage while said general operator is in motion.

49. The combination with a computing mechanism, including indexing means for effecting a preliminary representation or set-up of a number to be computed, a general operator, and means operated thereby when actuated for completing a computation in accordance with said preliminary representation or set-up as determined by said indexing means, of a computation-state-setting mechanism for varying the relation of parts of said indexing means, so as to selectively predetermine computations of different character, a state-setting-initiating device normally effective when actuated to cause a state-setting to be effected by said state-setting mechanism, and means controlled by said general operator for rendering said state-setting-initiating device incapable of effecting a setting operation of said state-setting mechanism while said general operator is in action.

50. The combination with a computing mechanism, of a subtraction-setting mechanism for said computing mechanism, a general operator for running up computations effected by said computing mechanism, a traveling carriage, tabulating mechanism for controlling the general movements of said carriage to bring the same to computing zones, the connections of said subtraction-setting mechanism to said carriage enabling the bringing into play of said subtraction-setting mechanism from said carriage, means for rendering said carriage controlled connections ineffective while said general operator is in motion, and means for rendering said carriage-controlled connections ineffective while said tabulating mechanism is in action.

51. In a machine of the character described, the combination with a rail, of a tappet pivotally mounted on said rail, a roller mounted on said tappet, a plurality of camming dogs pivotally mounted on said tappet, and means engaging said roller to raise said tappet to an effective position, so as to bring both dogs in action at the same time.
- 10 52. The combination with a computing mechanism, of state-controlling mechanism for said computing mechanism arranged to change the character of computation carried on by said computing mechanism, said state-controlling mechanism having a positively moving member, and a connection acting positively when unobstructed, and yielding forcedly when opposed in its action so as to prevent breakage of the parts.
- 15 53. The combination with registering means, of a series of numeral keys, an intermediate mechanism between said numeral keys and said registering means for temporarily accumulating a preliminary representation of a number as the numeral keys are struck, and arranged to transfer the same to said registering means, a carriage traveling to determine different computing zones or columns, and means actuated at the entrance of said carriage into a computing zone or column to determine whether said intermediate mechanism shall effect an adding or subtracting action for such zone.
- 20 54. The combination with a computing mechanism, of a subtraction-setting mechanism for said computing mechanism, a power drive for said subtraction-setting mechanism acting positively when brought into play, and a flexible connection permitting said power drive to act completely even where there is an interruption of or partial action of said subtraction-setting mechanism.
- 25 55. The combination with a totalizer having wheels always rotating in one direction for computing in a plurality of computing zones, of traveling means for determining the several computing zones, and subtraction-causing mechanism controlled by said traveling means as it enters a new zone to cause rotation of said computing wheels, in the one direction, different from the digits to be subtracted in the corresponding orders, and thereby effect a subtracting operation for the zone.
- 30 56. The combination with one or more groups of unirotational computing wheels, of a carriage traveling to determine different computing zones for said computing wheels and state-controlling means brought into play at the beginning of a computing zone to cause rotations of said computing wheels complementary to the digits being computed, so as to effect a subtracting operation for that zone.
- 35 57. In combination with a computing mechanism, including indexing means for effecting a preliminary representation or set-up of a number to be computed, and operating mechanism therefor for completing a computation in accordance with such preliminary representation, a set of number keys, a traveling carriage, means, comprising parts normally effective on movement of said carriage within the limits of a predetermined zone, for establishing co-operative relations between said keys and parts of said indexing means, a computation-state-setting mechanism for varying the relations of parts of said indexing means, so as to selectively cause said preliminary representation to be determinative of computations of different character, means, including parts normally caused to be operated on movement of said carriage into said zone, for causing an actuation of said state-setting mechanism to be effected, a manually settable key, and means controlled by said key when set for rendering all of said carriage-controlled parts ineffective when said carriage is in said zone.
- 40 58. In combination with a computing mechanism, including indexing means for effecting a preliminary representation or set-up of a number to be computed, and operating mechanism therefor for completing a computation in accordance with such preliminary representation, a set of number keys, a traveling carriage, means, comprising parts normally effective on movement of said carriage within the limits of a predetermined zone, for establishing co-operative relations between said keys and parts of said indexing means, a computation-state-setting mechanism for varying the relations of parts of said indexing means, so as to selectively cause said preliminary representation to be determinative of computations of different character, means, including parts normally caused to be operated on movement of said carriage into said zone, for causing an actuation of said state-setting mechanism to be effected, and a manually settable device capable of being rendered effective, at the will of the operative, to prevent an actuation of said state-setting mechanism when said carriage-controlled parts are brought into co-operative relation by movement of said carriage into said zone, so that said keys may be brought into co-operative relation with said indexing means for effecting a preliminary representation determinative of a computation of the character opposite to that which would normally be determined as a result of the actuation of said carriage-operated parts.
- 45 59. The combination with a totalizer, actuating mechanism therefor, and a traveling carriage, of means for changing the condition of the actuating mechanism, to cause

either addition or subtraction to be performed, a member for controlling the condition-changing means, means tending to actively drive said member, means for restraining said member, carriage-controlled means for releasing said restraining means, and a manually settable device capable of being rendered effective, at the will of the operative, to prevent the releasing of said restraining means, so as to maintain the

setting of said condition-changing means during an operation of said carriage-controlled-releasing means which would normally effect a change of condition of said actuating mechanism.
